United States Patent Office

Des. 211,392
Patented June 11, 1968

211,392

COMBINED FLASHLIGHT AND TOY

Leon D. Grebow, New York, N.Y.
(3850 Hudson Manor Terrace, Bronx, N.Y. 10463)

Filed Nov. 3, 1966, Ser. No. 4,533

Term of patent 14 years

(Cl. D48—24)

Fig. 1

The dominant features of my design reside in the full line portions shown.

I claim:

The ornamental design for a combined flashlight and toy, substantially as shown and described.
